UNITED STATES PATENT OFFICE.

ALICE R. SHEEHAN, OF PROVIDENCE, RHODE ISLAND, ASSIGNOR TO REVERE RUBBER COMPANY, A CORPORATION OF RHODE ISLAND.

DESIGN FOR A BATHING-CAP.

51,398.

Specification for Design.

Patented Oct. 16, 1917.

Application filed August 3, 1917. Serial No. 184,336. Term of patent 7 years.

To all whom it may concern:

Be it known that I, ALICE R. SHEEHAN, a citizen of the United States, residing at Providence, county of Providence, State of Rhode Island, have invented a new, original, and ornamental Design for a Bathing-Cap, of which the following is a specification, reference being had to the accompanying drawing, forming part thereof, in which—

The figure is a perspective of a bathing cap showing my design.

I claim:

The ornamental design for a bathing cap, as shown.

Signed at Providence, R. I., this 31st day of July, 1917.

ALICE R. SHEEHAN.
